UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

CURTAIN-BOX SPRING-LOCK.

1,256,051.

Specification of Letters Patent. Patented Feb. 12, 1918.

Application filed October 4, 1915. Serial No. 54,088.

To all whom it may concern:

Be it known that I, HARRY H. SCHROYER, a citizen of the United States, and a resident of the city of Chicago, in the county 5 of Cook and State of Illinois, have invented certain new and useful Improvements in Curtain-Box Spring-Locks; and I do hereby declare that the following is a full, clear, and exact description of the same, reference 10 being had to the accompanying drawings, and to the numerals of reference marked thereon, which form a part of this specification.

This invention relates to that type of 15 shield and mounting means particularly adapted for use with car window curtains of the type disclosed in my co-pending application for "revolving curtain shields", filed August 15th, 1914, Serial No. 856,932.

20 However, in the present construction, while the curtain roller is also mounted within and is bodily revolute with the curtain shield, the ends of the shield are formed to permit the shield when closed 25 to spring into a locked position.

It is an object therefore of this invention to construct a revolving shield pivotally mounted upon a window frame acting to afford a support for the curtain roll, and 30 so disposed as to effectually conceal the same from view in locked position, as well as protecting the curtain roll from unauthorized interference.

It is also an object of this invention to 35 construct a device adapted to support the curtain roll for use upon a car window concealing and as well protecting the curtain, and capable of being revolved from a locked position into a position out of use to expose 40 the curtain roll in operable position, permitting easy adjustments or replacements thereof to be made.

It is also an important object of this invention to construct a combined shield and 45 support for a curtain roll, said shield being eccentrically mounted upon a window frame, whereby when the shield is revolved into open position, the curtain roll is exposed to view, by such movement the shield assuming a position permitting easy adjustment 50 thereof, but, when the shield is revolved into closed position, the end members thereof spring into a locked position with the window frame support, thus eliminating the possibility of noisy vibration or

accidental opening of the shield taking place.

It is also an important object of this invention to provide in combination with a window frame, a detachable and adjustable 60 combined support and shield for a curtain roll, constructed with spring locking means for locking the shield with the window frame, and permitting the shield to be forced from locked to open position to permit 65 ready attachment and detachment of the curtain roll therefrom.

It is furthermore an object of this invention to construct a device supporting a curtain roll in concealed position upon a car 70 window, and capable of being sprung into a locked position with the window frame.

It is finally an object of this invention to construct a curtain shield and support for a car window, with the ends of the shield 75 formed to lock with the window frame when the shield is in closed position.

The invention (in a preferred form) is illustrated in the drawings and hereinafter more fully described.

80

In the drawings:

Figure 1 is a front elevation of the window of a car illustrating a device embodying the principles of my invention attached thereon.

85

Fig. 2 is an enlarged view of the curtain shield and upper portion of the window shown in Fig. 1.

Fig. 3 is an enlarged interior view taken on line 3-3, of Fig. 1, with parts shown in 90 elevation.

Fig. 4 is a vertical section taken on line 4-4, of Fig. 1, with the curtain roll removed.

Fig. 5 is a vertical section taken on line 95 5-5, of Fig. 4, with parts removed.

Fig. 6 is a vertical section partly broken away taken on line 6-6, of Fig. 3, with the shield and curtain roll removed.

Fig. 7 is a view similar to that shown 100 in Fig. 4, with the shield in open position.

Fig. 8 is a vertical section partly broken away, taken on line 8-8, of Fig. 1, showing the shield in raised position with the curtain roll removed.

105

Fig. 9 is a section taken on line 9-9, of Fig. 7, showing both ends of the casing.

As shown on the drawings:

The window posts of a car window are denoted by the reference numeral 1, and re- 110

movably secured thereon are suitable members 2, provided with grooves extending to within a short distance of the top of said window posts 1, thus affording vertical supporting plates 3 and 4, above said grooved portions. Cut or stamped from the outer edge of said plate 3, affording a slot 5, is a lug 6, which is bent inwardly as shown in Fig. 3. Releasably secured on the plate 3, by means of a screw 7, is a small plate 8, having a lug 9, integral therewith and bent at right angles from said plate 8, to fit into said slot 5, to partially fill the same, thus leaving an aperture 10, formed by the inner end of said slot 5. The plate 3, is provided with an aperture 11, in line with and directly to the rear of the aperture 10, and the plate 4, has formed therein apertures 12, and 13, in a horizontal line with one another and disposed directly opposite said apertures 10 and 11, respectively.

Mounted near the upper end of said window posts 1, are face plates 14, each of which has a cup shaped portion 15, extending outwardly therefrom. Rotatably mounted in the respective apertures 10 and 12, are pins 16, rigidly secured to a pair of substantially circular plate members 17, provided with indents 18, and which are integrally connected by means of a horizontally disposed hood or shield 19, which, when in closed position, engages closely beneath the overhanging edge of the curved end of members 15. The inner or rear edge of said shield 19, is bent at an acute angle, as indicated by the reference numeral 20, and the outer edge is bent around and back upon itself to form a substantially rectangular bead 21, said acute angled portion 20, and bead 21, alternately acting as stops to limit the movement of the shield into open and closed position.

A horizontal cornice member 22, rests upon said cup-shaped portions 15, and is secured at its ends upon said window 1, by means of screws or in any suitable manner, and extends across the window frame, affording a finished appearance to the structure. The lower edge of the cornice member 22, is so positioned as to be contacted by said acute angled portion 20, of the curtain shield when the same is revolved into closed position shown in Fig. 4. When the shield 19, is revolved into open position the acute angled member 20, moves back into the position shown in Fig. 7, and the rectangular beaded portion 21, swings upwardly and strikes against the lower surface of said cornice member 22, said cornice member thus affording a stop for the shield in open position.

60 Releasably attached to the top of the window frame and secured to said windowposts 1, by screws or other suitable means, is a channel iron 23, having a slot 24, therein to permit raising of the window sash. Said channel iron 23, overlaps said cornice mem-

ber 22, to hold the same in place and serve as a finishing member for the window frame.

Rigidly secured upon the inner surface of each of the rotatable end plates 17, of the shield 19, are roller supporting members 25, 70 and 26, respectively, the member 25, having a round recess 27, therein, and the member 26, having a notched U-shaped recess 28, opening outwardly therefrom. Said member 26, is adapted to receive therein the rectangular gudgeon 29, of a spring curtain roller 30, the rounded gudgeon 31, in the other end thereof fitting rotatably into the bearing member 25.

80 A curtain 32, is secured to and wound upon said roller 30, in the usual manner, and along its lower edge is provided with spring actuated stops 33, fitting into the channel guides 2, provided for the purpose, and actuatable by finger pieces 34, to move the curtain up 85 and down into any desired position of adjustment.

The operation is as follows:

90 The shield 19, when in the position shown in Fig. 4, entirely conceals the curtain roll from view, and as well protects the same from unauthorized interference or from damage. However, when it is desired to adjust, repair or replace the curtain, as the case may be, the hood is revolved into open 95 position by inserting the finger underneath the lower rectangular bead 21, thus forcing the detents 18, from the recesses 11 and 13, to permit revolving the hood and its end plates 17, upon the pins 16, until the head 100 21, strikes the cornice member 22, secured across the window frame. When the shield is revolved into closed position it is revolved downwardly from the position shown in Fig. 7, until the acute angled portion 20, 105 contacts with the lower portion of the cornice member 22, and the indents 18 spring into locked position in the apertures 11, and 13, in the plates 3, and 4, thus preventing accidental detachment of the roller and as 110 well maintaining the shield securely in position incapable of vibration. Due to the detachable character of the cornice member 22, and the channel iron 23, the same may be readily removed to permit adjustment or 115 replacement of parts.

I am aware that the details of construction may be varied through a wide range without departing from the principles of this invention. I therefore do not purpose 120 limiting the patent granted otherwise than necessitated by the prior art.

I claim as my invention:

1. The combination with a window frame, of transverse members removably secured 125 thereacross and forming a casing, a curtain shield pivotally mounted therebeneath, and a curtain roller mounted within said shield, one of said transverse members acting also as a stop for said shield in the opening and 130

5 closing movements thereof, the other of said transverse members fitting above the top of the window frame and overlapping said first-mentioned member to hold the same in place.

10 2. In a device of the class described, the combination with a window frame, of curtain guides secured thereto, face plates having cup-shaped portions integral therewith detachably mounted on said window frame, a curtain shield rotatively mounted at the upper end of the window frame the ends thereof adapted slidably to engage within said cup-shaped portions of said face plates, 15 a curtain roller mounted within said shield, and a curtain thereon adapted to be extended and held in proper position by said guides.

20 3. In a device of the class described, the combination with a window frame having apertures therein, of a curtain roll, a revoluble shield therefor adapted to be moved into open and closed position around said curtain roll, and indents formed in the 25 ends of said shield adapted to engage in said apertures to hold the shield in locked position.

25 4. In a device of the class described, a window frame, a curtain roller, a revoluble shield therefor in which said roller is supported, said frame having an aperture on one side near the upper end thereof and a slot on the other side thereof opposite said aperture, a pin on each end of said shield adapted to engage in said aperture and said slot to support said shield, a plate detachably mounted on said frame, a lug integral

therewith and bent at right angles thereto, said lug adapted to fit into said slot to positively hold said shield in position, and 40 means on said shield adapted to be sprung into locking position with the window frame when said shield is moved into closed position.

45 5. In a device of the class described, a window frame having an aperture on each of its inner sides near the upper end thereof, a curtain roll, a revoluble shield therefor adapted to be moved into open and closed position around said curtain roll, and 50 oppositely disposed indents formed in the ends of said shield, said indents adapted to engage said apertures when said shield is moved into closed position.

55 6. In a device of the class described, a window frame having an indent in each side near the upper end thereof, a curtain roller, a revoluble shield therefor in which said roller is supported, indents in the ends of said shield adapted to be sprung into locking engagement with said frame indents when said shield is moved into closed position, and means for retaining said roller within the shield when the shield is in closed 60 position, and permitting detachment of the roller when the shield is in an open position.

In testimony whereof I have hereunto subscribed my name in the presence of two subscribing witnesses.

HARRY H. SCHROYER.
